United States Patent

Des. 234,499
Patented Mar. 18, 1975

234,499

VEHICLE BODY

Henry Altepeter, 1014 S. 10th Ave.,
St. Charles, Ill. 60134

Filed Nov. 8, 1973, Ser. No. 414,176

Term of patent 14 years

Int. Cl. D12—08

U.S. Cl. D12—85

FIG. 1 is a perspective view of a vehicle body showing my new design, it being understood that the broken lines are for illustrative purposes only;

FIG. 2 is a front elevational view thereof;

FIG. 3 is a side elevational view of one side of the vehicle body, it being understood that the opposite side is a mirror image thereof;

FIG. 4 is a top plan view thereof; and

FIG. 5 is a rear elevational view thereof.

I claim:

The ornamental design for a vehicle body, substantially as shown and described.
